LLC(57) CLAIM

I claim the ornamental design for the flower stand, as shown and described.

DESCRIPTION

FIG. 1 is a perspective view of the flower stand showing my new design.

FIG. 2 is a front, rear, left side, or right side elevational view thereof;

FIG. 3 is a top plan view thereof; and,

FIG. 4 is a bottom plan view thereof.

The broken lines in the figures show portions of the flower stand that form no part of the claimed design.
